MEANS FOR MIXING SAMPLES

Ben M. Hawes, Santa Cruz, Calif.

Application June 21, 1938, Serial No. 215,053

4 Claims. (Cl. 259—54)

This invention relates to mixing devices and particularly to means for mixing relatively small samples of dry, pulverized materials such as clay, rock and Portland cement samples, and for agitating mixtures of cement and other dry pulverized material with water for the purpose of securing a perfect sludge free from lumps.

The general object of the invention is to provide a very simple mechanism for this purpose which has been found, however, to be thoroughly effective and in which the material to be mixed is disposed in a cylindrical container as, for instance, a bottle or jar, and then rolled for as long a time as necessary, while at the same time the container is tipped longitudinally.

A further object is to provide means whereby the tipping action above referred to may be at relatively long intervals in comparison with the rolling action and may be of various degrees of amplitude.

Other objects will appear in the course of the following description.

My invention is illustrated in the accompanying drawing wherein:

Fig. 1 is a side elevation of the testing mixer constructed in accordance with my invention.

Fig. 2 is a section on the line 2—2 of Fig. 1.

Fig. 3 is a top plan view of the construction shown in Fig. 1.

Fig. 4 is an elevation of the variable throw crank.

Fig. 5 is a fragmentary section through the rim of the drive wheel on the line 5—5 of Fig. 3.

One particular embodiment of my invention is illustrated in the accompanying drawing, and in this embodiment as illustrated, 10 designates a base of any suitable character and 11 uprights mounted upon the base. The motor, which is designated 12, has its shaft 13 frictionally engaged with the friction wheel 14 in turn having an attached barrel 15 constituting in a sense a friction pinion. This pinion or barrel 15 in turn engages a gear wheel 16 having a barrel or friction pinion 16a in turn frictionally engaging a wheel 17 mounted upon a shaft 18.

Pivoted upon the uprights 11 is a frame composed of the longitudinal members 19 and the transverse members 20. This frame is pivoted upon trunnions 21 disposed in the uprights 11. Mounted within the frame are the longitudinal rollers 22 which extend the length of the frame and bear frictionally against the friction wheel 17. It is obvious now that the rollers 22 will be constantly turned in one direction when the machine is in operation.

For the purpose of oscillating the frame composed of the members 19 and 20, I provide a crank 23 having an adjustable crank pin 25 which is connected by a link 24 to the free end of the roller carrying frame. I do not wish to be limited to any particular means for driving this crank, but I have shown for this purpose a shaft 26 which carries the crank and which is provided with a friction wheel 27 in turn driven from a friction wheel 28 mounted upon the shaft 18. This will drive the shaft 26 and the crank 23 at a reduced speed relative to the speed of shaft 18 and the speed of rotation of the rollers 22.

In the use of this device, the sample to be treated is placed in a bottle or other cylindrical container (not shown) which in turn is placed upon the rollers 22 and rotate the cylindrical container continuously in one direction. Simultaneously the frame supporting the rollers is oscillated vertically and thus the bottle or other container is tilted in opposite directions. The rolling motion mixes the sample and the rocking motion of the roller frame aids the mixing process by building up the sample material first in one end of the bottle and then in the other, thus preventing any possible segregation of materials in one end of the container. It will be seen from Fig. 2 that the rim of wheel 17, which is preferably transversely convex and rubber-surfaced (see Fig. 5) is disposed, as before stated, in the same plane as the trunnions or pivots for the rocking frame so that the roller frame actually teeters or rocks on the drive wheel 17.

In order to provide for using this apparatus for mixing materials in an open-ended container, some provision must be made to stop or lock the oscillating action at any point, so that the sample can be rolled at an angle but kept from spilling out of the open-ended container. To this end, I have illustrated in Fig. 1 the shaft 26 as being formed in two sections with a clutch 29 disposed between these two sections so that that section carrying the crank disk 23 may be kept from revolving, and for the purpose of holding the crank disk 23 at any desired position to secure a desired angle for the roller supporting frame 19, I have provided a brake 30 which engages a brake drum 31 on the shaft 26. It is to be understood that any means for holding the outer section on shaft 26 from rotation is within the purview of this invention. It will be obvious also that by shifting the crank pin 25 inward in the radial slot in disk 23, the tilting motion may be reduced to a minimum, so that open-ended containers may be rolled and at

the same time oscillated without discharging the contents of the container.

When rolling an open container at a relatively steep angle, provision should be made for preventing the sliding movement of the container on the rollers and when rolling a plurality of containers on the rollers 22, it is desirable to prevent these containers from sliding together at the lower end of the roller frame. To this end, I have provided a longitudinally extending rod 32 attached to the frame 19 and extending from end to end thereof on a level slightly higher than the frame and on this rod may be mounted one or more collars 33, each collar having an arm 34 extending across the top of the rollers. The collar 33 is held in position upon the rod 32 by means of a set screw 35. It will be understood that as many of these collars 33 and arms 34 may be used as desired or necessary in order to keep the containers from sliding through the lower end of a steeply inclined frame 19 or from sliding back and forth in case said frame 19 is oscillated.

This device under actual tests has been found to do a very thorough job of mixing in a relatively few minutes. This device saves time and labor as a sample coming into the laboratory can be placed on a mixer and rolled any length of time while the operator does other work. Ordinarily, such a sample would have to be rolled on cloth before analysis. Both small and large sample containers can be rolled on the mixer at the same time, for instance, with rollers 2" apart, it would be possible to roll a 2½" diameter bottle as well as one of 12" diameter simultaneously.

The device can be also used for mixing powdered drugs and, under these circumstances, the same container would always be used to mix the same materials, thus eliminating the necessity of thoroughly cleaning containers after use and lessening danger of contamination.

It will also be seen that the device is small, compact, light, takes up small space and is easy to move.

While I have illustrated certain details of construction and arrangement of parts, I do not wish to be limited thereto, particularly as regards the driving means for the rollers and the means for oscillating the roller supporting frame.

What is claimed is:

1. A mixing device of the character described, including a roller supporting frame, a pair of

longitudinally extending rollers mounted thereon and adapted to support a cylindrical container, a drive wheel for said rollers disposed in the same plane as the pivotal axis of the frame and upon which drive wheel rollers oscillate, power actuated means for driving the wheel, and power actuated means for securing an oscillation of the frame in a vertical plane.

2. A mixing device, including a frame mounted for oscillation in a vertical plane, a pair of longitudinally extending rollers mounted upon the frame and adapted to support a cylindrical container, means for rotating said rollers, including a friction wheel engaging both of said rollers and disposed in the same plane as the pivotal center of the frame whereby the rollers will oscillate on said friction wheel, a motor, a train of gears between the motor and said friction wheel, a crank operatively connected to said frame to oscillate it, and means operatively connected to the motor and driven thereby for rotating said crank.

3. A mixing device of the character described, including a roller supporting frame mounted for tilting movement in a vertical plane, a pair of longitudinally extending rollers mounted thereon and adapted to support a cylindrical container, a drive wheel for said rollers having its rim disposed in the same plane as the pivotal axis of the frame and upon which drive wheel the rollers may oscillate, power actuated means for driving the wheel, and means for holding the roller supporting frame at any desired angle to the horizontal.

4. A mixing device, including a frame pivotally mounted for oscillation in a vertical plane, a pair of longitudinally extending rollers mounted upon the frame and adapted to support a cylindrical container, means for rotating said rollers, including a friction wheel engaging both of said rollers and having its rim disposed in the same plane as the pivotal center of the frame whereby the rollers will oscillate on said friction wheel, a shaft upon which the friction wheel is mounted, the shaft being formed in two sections, a clutch connection between said sections of the shaft, a crank mounted upon the outer section of the shaft remote from the friction wheel, means operatively connecting the crank to the oscillatable frame, and means for holding the outer section of the shaft from rotation when the clutch between the two sections is disengaged.
